UNITED STATES PATENT OFFICE.

SAMUEL P. BUSH, OF COLUMBUS, OHIO, ASSIGNOR TO THE BUCKEYE STEEL CASTINGS COMPANY, OF COLUMBUS, OHIO.

CAR-TRUCK SIDE FRAME.

1,110,883.

Specification of Letters Patent. Patented Sept. 15, 1914.

Application filed May 2, 1914. Serial No. 836,043.

To all whom it may concern:

Be it known that I, SAMUEL P. BUSH, of Columbus, in the county of Franklin and State of Ohio, have invented certain new and useful Improvements in Car-Truck Side Frames; and I do hereby declare the following to be a full, clear, and exact description of the invention, such as will enable others skilled in the art to which it appertains to make and use the same.

My invention relates to an improvement in car truck side frame; and is an improvement on the construction disclosed in application Serial Number 795,300 filed by me

15 October 15th, 1913.

With the construction disclosed in the application above referred to, the journal boxes are specially made with wide flanges to engage the bolt head and washer which hold

23 the journal box within the truck side frame.

The object of this invention is to provide means which operate only in an emergency to prevent the separation of the journal box from the truck side frame, and which are designed for use with the ordinary makes

25 of journal boxes of the pedestal type, and my invention consists in the details of construction as will be more fully described and pointed out in the claims.

30 In the accompanying drawings Figure 1 is a view in elevation of one end of a side frame showing the journal box in place, and Fig. 2 is a view in section on the line A—B, of Fig. 1.

35 1 represents the truck side frame having pedestal jaws 2 and 3 for the axle or journal box 4, which may be of any standard make. Journal boxes used on some car trucks, are provided with side flanges 5 which engage

40 the pedestal jaws for holding the boxes in

place within the truck frame, and to adapt my improvement to these boxes I make the inner jaw 2 of the pedestal longer than the jaw 3, when necessary so that the means for

45 holding the box in place may be located below the lower ends of said side flanges. It

will of course be understood that both jaws 2 and 3 of the pedestal may be of the same length, but in the present instance I have

50 shown the inner jaws 2 longer than the outer jaws, the additional length being primarily for the attachment of the journal box holding means in a plane below the lower ends of the side flanges of the box.

55 The pedestal jaws 2 are each provided

on their opposite faces, in a plane below the side flanges of the boxes, with the recessed seats 6 and with a bolt hole passing through the pedestal and communicating with both recesses.

60

Passing through the hole in the jaw, is the bolt 7, provided at one end with an enlarged rectangular head 8 the inner portion of which rests within a recessed seat 6, and at its other end with a washer 9 also resting

65

in a recess and held in place by a nut 10 screwed onto the end of the bolt. The washer 9 corresponds in size and shape to the head 8 of the bolt, and both of them are made sufficiently long to project under the

70

flange 5 at one side of the box and lock the latter against accidental displacement. With this construction the head of the bolt and the washer are seated in recesses, and are held therein by the bolt, so that the bolt

75

is not subjected to any stress other than that put upon it by screwing up of the nut, the head of the bolt, or the washer, or both taking all stresses that may be imposed by contact with the flanges of the box and transmitting them to the frame. The bolt and its

80

head and washer are simply means for preventing separation of the parts only in an emergency, as for instance, in the derailment of a car, and are so located with relation to the box as not to interfere with the limited lateral motion of the box with relation to the side frame, or a limited lateral movement of the side frame with relation

85

to the boxes. It is not essential that both the head of the bolt and the washer should engage the flanges of the box, as the engagement of either the head of the bolt, or the washer with one flange of the box would be sufficient.

90

By the construction of frame, boxes of any standard make can be used without any change, and when in place will be free to have all the movements necessary or desirable but will be held against possibility of accidental displacement.

95

Having fully described my invention what I claim as new and desire to secure by Letters-Patent, is:

100

1. The combination of a truck side frame having pedestal jaws, one of which is provided on its side face with an open recessed seat accessible when the journal box is in place and a member fitting in said recessed seat and held in place by a bolt, said mem-

105

110

2
ber being in a position to engage a flange of
a journal box in the event of derailment.

2. The combination of a truck side frame
having pedestal jaws one of which is pro-
vided with a recessed seat on each side face,
a bolt the head of which has bearing in one
of said recessed seats, and a washer on said
bolt and mounted in the other recessed seat,
the said head and washer being in positions
to engage the flanges of a journal box and
prevent its separation from the truck in the
event of derailment.

3. The combination of a truck side frame
having pedestal jaws one of which is longer

15
than the other, the longer jaw being pro-
vided with a recessed seat in its side face
adjacent the lower end of the jaw, and a
member fitting in said seat and held in place
by a bolt, the said member being in a posi-
tion to engage a flange of a journal box in 20
the event of accidental derailment.

In testimony whereof, I have signed this
specification in the presence of two subscrib-
ing witnesses.

SAMUEL P. BUSH.
